UNITED STATES PATENT OFFICE.

JOHN W. SWARTZ, OF LAKEWOOD, OHIO.

COMBINED NAME-CARD HOLDER AND LOCK FOR AN OFFICE SEAL PRESS.

Application filed February 2, 1925. Serial No. 6,268.

The objects of the invention are to provide a combined name plate holder and locking device for a seal pressing device which is simply and inexpensively constructed and 5 is attachable to any cast metal seal press such as are commonly employed in impressing notary and corporation or other documentary seals upon paper.

The device is slidably mounted upon the 10 pivot shaft or pin for the lever of the seal press—and comprises a folded sheet of metal having rearwardly extending wings slotted for adjustment upon said pivot pin—and having its front portion positioned vertically and constructed to receive a name- 15 plate.

The invention is hereafter more fully described, illustrated in the accompanying drawings and specifically pointed out in the 20 claims.

In the accompanying drawings Fig. 1 is a vertical section of a seal press showing the manner of applying the device thereto; Fig. 2 is an end elevation thereof; Fig. 3 is a plan thereof; Fig. 4 is a section showing the lever in the lock position and Fig. 5 is a perspective of the combined name-plate holder and locking device. Fig. 6 is a perspective of the device formed in two por- 30 tions.

In these views, 1 represents standard of the die press; 2 is the base; 3 is the elevated die thereon and 4 is the matrix die which is mounted upon the shaft (5) vertically 35 movable in the standard, and 6 is the lever pivoted upon the pin (7) and provided with the cam (8) which engages with and depresses the shaft (5) a spring (9) returns the shaft when released by the lever. The 40 lever is also provided with the projection (10) which normally engages with the shoulder (10¹) upon the upper end of the shaft to prevent the lever from moving forward beyond the vertical position.

45 These parts are employed in the construction of the ordinary seal press and do not apply to the present invention.

In the attached device which includes this invention 11, 11 are wings which are turned

backward from a transverse body (12) having a locking upper edge (13) and are longitudinally slotted at 14, 14 and the pivot pin (7) passes through them and supports the device in place.

When the lever is depressed to engage 55 the matrix die with the elevated portion of the die beneath, the body (12) is moved backward to engage the edge (13) with the projection (10) upon the lever, thus locking 60 the lever and dies in their pressing position.

In front of the transverse body (12) is positioned the name plate holder or frame (15), which may be connected with the body (12) at its lower edge at 16 and the vertical ends of the frame (15) are turned inward and backward at 17, 17, thus cooperating with the connecting portion (16) to form a convenient rest and retaining means for a name plate.

The device is preferably composed of integrally attached parts and is readily formed of sheet metal—but may be made in any desired manner within the spirit and scope of the claims.

In Fig. 6 the device is shown formed in two portions attached together.

Here the card holder 15 is shown riveted back to back to the body 12, and card holding flanges 16' and 17' turn outwardly therefrom.

Having described the invention what I claim as new and desire to secure by Letters Patent is:—

1. In a combined locking device and name plate holder for a seal press, a body portion provided with rearwardly extending wings, said wings being horizontally slotted, said body having a locking upper edge and a name card or plate having card holding members on its vertical and lower edges and rigidly connected with said body.

2. The combination with the pivoted lever of a seal press and pivot pin therefor of a combined lock and name card holder therefor comprising a body portion provided with rearwardly extending slotted wings through the slots in which said pivot

pin passes and having an upper locking edge, said lever being provided with a shoulder and said locking edge being adapted to engage with said shoulder on said lever, when said lever is in the pressing position.

3. In a card or name plate holder for an office seal press, the combination with the lever and pivot pin therefor and standards

of said press of a metal name card or plate holder, and slotted rearwardly extending wings secured to said holder said wings being adjustably mounted upon said pivot pin.

In testimony whereof, I hereunto set my hand this 10th day of October, 1924.

JOHN W. SWARTZ.
